[57] CLAIM

The ornamental design for an element of a shoe upper, as shown and described.

DESCRIPTION

FIG. 1 is a left side elevational view of a shoe showing our new design;

FIG. 2 is a right side elevational view thereof;

FIG. 3 is a top plan view thereof;

FIG. 4 is a front elevational view thereof; and

FIG. 5 is a rear elevational view thereof.

The broken line showing of a shoe in FIGS. 1-5 is environmental only and forms no part of the claimed design.

*FIG. 1.**FIG. 2.***FIG. 3.****FIG. 4.****FIG. 5.**
